CLOTHESPIN

Fred S. Clark, New York, N. Y.

Application April 2, 1948, Serial No. 145,495

Term of patent 14 years

(Cl. D17—6)

To all whom it may concern:

Be it known that I, Fred S. Clark, a citizen of the United States and a resident of New York city, and the county and State of New York, have invented a new, original, and ornamental Design for a Clothespin, of which the following is a specification, reference being had to the accompanying, forming a part hereof.

My design for a one-piece clothespin, comprised of a wide stirrup-shaped front portion and a narrow, straight back portion joined by a circular bend at the top, is characterized by the inwardly curving bottom edge of the narrow back portion in association with the inwardly curving bottom edge of the stirrup-shaped opening in the wide front portion, the two curving edges being of substantially the same width and in substantial alignment, all as shown.

I claim:

The ornamental design for a clothespin, as shown and described.

FRED S. CLARK.
